EXPANDED METAL LATH

Edwin W. Miller, Glendale, Calif., assignor to
Edmund P. Burke, Los Angeles, Calif.

Application April 30, 1938, Serial No. 205,266

6 Claims. (Cl. 72—117)

My invention relates to expanded metal lath and has for its object to provide an expanded metal lath which is stronger, more rigid, more beautiful in design, and more practical and efficient than present designs.

In the manufacture of my improved metal lath, the finished product is made of sheet metal so slitted and stretched or expanded that the design resulting is that of rows of triangles having straight, stretched sides, each row having said triangles alternately in opposite directions, the two sides of adjacent triangles forming also the two sides of a reversed triangle therebetween. In this form the base of each triangle is formed by two short lengths of material and each of the two sides of a single length of material. The reticular sheet of expanded metal is characterized by a triangular network in which the bases of adjacent triangles are in straight, stretched strands or lines, and the sides of said triangles form parallel lines diagonally positioned in opposite directions. The result is such rigidity that said metal lath cannot be stretched transversely, or in the line of the parallel bases, which are stretched taut, or vertically because of the diagonal positions of the long sides of the triangles formed as the slitted metal sheet is expanded or stretched to tautness in the formation of the metal lath. Moreover, the lath of this invention resists compressive forces applied in the plane of the expanded metal sheet either laterally, transversely or along diagonals to the edges of the sheet.

In order to more fully explain my invention, I have illustrated an embodiment of the same on the accompanying sheet of drawings, in which:

Figure 1 is a section of sheet metal shown slit-ted or cut as the first step in the formation of my improved metal lath;

Figure 2 is the same sheet partly expanded or pulled apart;

Figure 3 is an enlarged view of a portion of a metal lath embodying my invention; and Fig. 4 is a plan view of that shown in Fig. 3.

Referring in more detail to the drawing, a section of a sheet of metal suitable for the manufacture of lath is indicated at 5. This sheet is provided with parallel rows of slits in alignment, such as the slits 6 and 7, the slits in each row being interrupted by uncut spaces such as the spaces 6' and 7'. Generally, these uncut spaces between opposing ends of slits in a row are shorter than the length of the slits in such row. The uncut spaces or gaps in alternate rows are in transverse alignment so that the uncut spaces

6' are indicated in an alignment transverse to the rows of slits. The uncut spaces in intermediate rows are also in transverse alignment which is different from the alignment of the spaces 6'. The opposing ends of aligned slits in the intermediate rows should overlap a slit in an adjacent row and the amount of overlap should differ. For example, 16 and 16' denote the opposing ends of slits 6 in a row, such opposing ends being separated by an uncut portion 6'. These opposing ends of the slits 6 overlap the adjacent slit 7 by distances differing from each other. It will be noted that the end 16 of the slit 6 overlaps the slit 7 by a very material distance whereas the end 16' of the aligned slit 6 overlaps the slit 7 by a shorter distance. Pairs of gaps or uncut portions are thus formed, each pair being designated 8, and such gaps form the junctions 8' in the expanded sheet as indicated in Fig. 2 in particular.

As said slitted sheet is expanded or pulled said slits open up, as indicated in Fig. 2, and this is done by pulling the left hand edge out, or away from the sheet, and the right hand edge back, or, with the drawing lying flat on the desk, the left hand edge is pulled up and the right hand edge would be pulled down, or in the opposite direction. This results in separating the sheet first into the form shown in Fig. 2, and then into the finished form shown in Fig. 3.

The short connecting portions, designated 9, 9, between the two transverse rows of gaps, as they are stretched from the straight base, or short sides, of the triangles, as will be clear from Fig. 3. The base of each triangle is thus common to portions of the base of two other triangles. The long connecting portions, designated 10, 10, form the long sides of the triangles. It is to be noted also that these long sides of the triangular forms are in diagonal alignment in opposite directions and that the short connecting portions 9, 9, are in straight lines, and that between said straight base lines are the triangular forms alternately in opposite positions. The precise shape of the triangles formed in the expanded lath depends somewhat upon the distance separating the gaps 8 heretofore mentioned.

This construction and arrangement gives great strength transversely, with no stretching possible, and there is also increased strength in lines longitudinally of the triangles and also diagonally. In other words, there are parallel lines of strength which will not yield or stretch, making for rigidity, for all angles are reinforced by connections with other angles.

It is to be noted that the resulting expanded sheet is substantially flat, the sides and bases of all triangles lying in a common plane. During the expanding of the sheet in width, the length of the sheet has been reduced but all sides and bases of the triangles have been subjected to substantially the same amount of stress during expansion.

While I have shown and described in detail one practical embodiment of my invention, I am aware that changes may be made in details of construction without departing from the spirit thereof, and I do not, therefore, limit my invention to the showing made, except as I may be limited by the hereto appended claims forming a part of my application.

I claim:

1. A sheet metal blank slotted with parallel cuts, alternate cuts being interrupted in different positions longitudinally of said cuts, the interruptions of alternate cuts forming one row transversely of said cuts and the interruptions of the other alternate cuts forming another row transversely of said cuts, said two rows of uncut portions transversely of the cuts constituting a pair, the pairs of uncut portions being further apart than the rows of each pair, whereby when said sheet is expanded laterally, the strands between said cuts form the long sides of triangular forms and the shorter strands form the bases of said triangular forms, there being two rows of overlapping triangular forms between two lines of bases.

2. Expanded metal lath made of sheet metal, slotted with parallel cuts with short interruptions in said cuts, the interruptions of alternate cuts forming rows of interruptions transversely of said sheet metal, said rows being in pairs, and the pairs of rows being further apart longitudinally than the interruptions of each pair, where-

by when the strands are expanded, the shorter strands between the interruptions of each pair form straight line bases of triangles, and the longer strands between the pairs of interruptions form the longer sides of the triangles.

3. A sheet metal blank provided with parallel rows of slits in alignment, uncut spaces between ends of slits in a row being shorter than the length of each slit, the uncut spaces in alternate rows being in transverse alignment; the uncut spaces in intermediate rows being in a different transverse alignment, the opposing ends of aligned slits in said intermediate rows overlapping a slit in an adjacent row by distances differing from each other.

4. As an article of manufacture, a substantially flat reticular sheet of expanded metal, the metal forming triangles, such triangles being arranged in rows with their bases in a substantially straight line, the base of each triangle being common to portions of the bases of two adjacent triangles.

5. As an article of manufacture, a substantially flat reticular sheet of expanded metal, the metal forming triangles, such triangles being arranged in rows, the base of each triangle being joined substantially at its mid point to the intersection of two sides of adjacent triangles.

6. An article of manufacture substantially as shown and described and consisting of a substantially flat sheet of reticulated metal, the reticulations forming triangles, the base of each triangle being common to portions of the bases of two adjacent triangles, said bases forming straight lines in alignment with each other, the sides of said triangles being in substantially diagonal alignment whereby the sheet has rigidity and strength against deformation in various directions.

EDWIN W. MILLER.
